10 Claims. (Cl. 96—60)

In many photographic, and more especially color photographic processes there arises the necessity of removing a metallic silver image or oxidizing it to a metal salt image, for example, without attacking a color image.

While it is generally easy to remove metallic silver completely from single-layer materials that are free from color couplers or dyestuffs, this is often difficult in the case of multi-layer or mixed grain emulsion materials containing dyestuffs, because there remains in the area from which silver has been removed a faint, dark colored residual image, which may consist of silver sulfide or of silver enclosed by dyestuff, and which is particularly troublesome in the case of images to be viewed by reflected light.

To oxidize completely silver images in materials that have been subjected to color development numerous proposals have been made for activating the usual ferricyanide baths or replacing them by baths of a different nature.

The problem of the complete removal of metallic silver arises also in the silver dye bleaching process in which, as is known, dyestuffs are bleached out in single-layer or multi-layer materials in dependence on the amount of metallic silver locally present in the photographic image, and any remaining metallic silver must be subsequently removed.

The material to be processed generally comprises a support on which are coated a plurality of light sensitive silver halide emulsions, which may be in the form of layers or granules and which contain bleachable dyestuffs in a diffusion-resistant form. After exposure, development and fixation, the dyestuffs are bleached in dependence on the amount of silver locally present in the silver image. This is generally carried out in a bath which contains an acid, a substance capable of forming silver complexes, such as thiourea, and a bleaching catalyst.

When the material is subsequently treated in a known silver bleaching bath, for example, a bath containing copper sulfate, sodium chloride and hydrochloric acid, the metallic silver is not completely oxidized, or impurities accompanying the silver are not completely removed, so that, after treatment in a fixing bath following upon the silver bleaching bath, there is left a residual density which becomes apparent in images to be viewed by reflected light as poor remission in the light areas of the image. While it is possible to improve the result by repeated alternate treatments with the silver bleaching bath and the fixing bath, this method is very troublesome, so that there is a need for a silver bleaching bath which completely oxidizes the metallic silver in a single, short treatment.

The present invention is based on the observation that a silver bleaching bath which contains a hydrohalic acid, a cupric salt and water-soluble aliphatic carboxylic acid converts metallic silver in a very short time and quantitatively into silver halide, even when the said silver bleaching bath is used after a dye bleaching bath that causes the silver to become less reactive. Accordingly, the invention provides for rehalogenating metallic silver in a photographic material, a bath which contains a cupric

2

salt, a hydrohalic acid and a water-soluble aliphatic carboxylic acid.

As the hydrohalic acid there is preferably used hydrochloric or hydrobromic acid. While it is possible to form these acids by double decomposition, for example, by incorporating in the bath potassium bromide and sulfuric acid, the best results have been obtained with baths which contain no or a very small amount of metal ions, for example, alkali metal ions, other than the copper ions, and which are practically free from sulfate ions. Therefore baths which contain, instead of the often used copper sulfate, other copper salts, for example, copper acetate or copper nitrate, are preferred. The baths advantageously contain about 0.5 to 2.0 mols of the hydrohalic acid and about 0.1 to 1.0 mol of the copper salt per liter.

As aliphatic carboxylic acids there may be mentioned, for example, unsaturated acids and polycarboxylic acids, though other acids may likewise be used, provided that 20 they contain no basic substituents and are water-soluble. The acids are advantageously composed exclusively of carbon, hydrogen and oxygen, and advantageously contain not more than 7 carbon atoms. It is of advantage to use acids capable of forming water-soluble copper compounds.

As examples of such acids there may be mentioned: acetic acid, lactic acid, cyanoacetic acid, acrylic acid, succinic acid, tartaric acid, citric acid, and maleic acid.

As a rule, the best results are achieved with acrylic acid and citric acid.

The mechanism behind the action of these acids has not yet been completely elucidated. It is probable that they act, on one hand, as solvents or solution promoters for the products that passivate the metallic silver, such as dyestuff fission products and thiourea complexes, and radicals of bleaching catalysts or of filter dyestuffs. However, since, on the other hand, these acids are capable of forming complexes with the copper ions, they are able to modify the oxidation conditions. The acids give their optimum effect at a concentration ranging from about 1 to 15%, and preferably 2 to 12%.

Accordingly, the preferred silver bleaching baths of the invention are those which contain, per liter, about 0.5 to 2 mols of a hydrohalic acid, such as hydrochloric acid, 0.5 mol of a copper salt, such as copper nitrate, and about 2 to 12% of an aliphatic carboxylic acid, such as acrylic or citric acid.

The baths can be further improved by adding thereto a small proportion of a surface-active agent, for example, a 50 polyglycol ether of a higher fatty alcohol, and especially a fluorinated aliphatic carboxylic acid such as described, for example, in U.S. specification No. 2,904,515.

The baths of the invention for rehalogenating metallic silver are suitable for use in all processes in which strongly 55 acid baths are not harmful. They are therefore suitable for use in those color photographic processes in which dyestuffs are not decomposed by acid, more especially, for the silver dye bleaching process. In the known method of carrying out the silver dye bleaching process, in which 60 the silver bleaching bath is applied after an acid dye bleaching bath, the baths of the invention are superior to the known silver bleaching baths. They bring about more rapidly the complete rehalogenation of metallic silver or complete removal of the impurities associated with the silver in multilayer materials to be viewed by reflected light so that, after subsequent removal of the silver halide in a fixing bath, clearer pictures and above all better whites, are obtained.

The azo-dyestuffs suitable for use in the silver dye 70 bleaching process have in general a good resistance and satisfactory stability to the rehalogenation baths of the invention, but there are cases in which the dyestuffs are ad-

versely affected when the bath has a very high concentration of aliphatic carboxylic acid. In such cases the addition of an organic base or of a salt thereof to the rehalogenation bath protects the dyestuff from oxidation without impairing the action of the bath on the silver to be rehalogenated or on the dark impurities accompanying the silver. Especially suitable bases are biguanides such, for example, as diphenyl-4:4'-dibiguanide, in a concentration below 1%. While baths containing no base give in many cases, though not always, satisfactory results, baths that contain a base as aforesaid are more generally applicable.

The following examples illustrate the invention:

Example 1

A white-reflecting support was coated with a layer of a red-sensitized silver bromide emulsion containing a diffusion-resistant blue-green azo-dyestuff, this layer was coated with a green-sensitized silver bromide gelatine emulsion containing a diffusion-resistant purple azo-dyestuff, the latter layer was coated with a yellow filter layer, and the filter layer was coated with the topmost layer of a non-sensitized silver bromide gelatine emulsion containing a diffusion-resistant yellow azo-dyestuff.

The material was exposed, developed, fixed and then bleached in a bath containing hydrochloric acid, sodium chloride, thiourea and 2:3-aminohydroxyphenazine, whereby all dyestuff in the areas that had been exposed to white light were destroyed. The material was thoroughly washed and bleached for 10 minutes at 24° C. in one of the silver bleaching baths described below, once more washed, fixed, washed and dried. The densities of the exposed areas as viewed by reflected light were then measured.

As a measure of the action of the silver bleaching bath there are given below the values for $\log I_0/I_R$ for blue light, in which I_0 is the intensity of the incident light and I_R is the intensity of the remitted light. The corresponding values for green and red light are smaller, but they vary relatively to each other in a similar ratio.

(A) For a known bath of the composition:

Sodium chloride _____ grams 100
Crystal copper sulfate _____ grams 100
Hydrochloric acid 37% strength _____ ml 100
Water to make 1 liter.

The $\log I_0/I_R$ value was found to be 0.32. The known ferricyanide baths did not produce any more favorable results; above, all, they produced spotty images which made accurate measurements impossible.

(B) For a bath in accordance with the invention having the composition:

Hydrochloric acid 37% _____ ml 90
Copper nitrate, $Cu(NO_3)_2 \cdot 3H_2O$ _____ grams 135
Acetic acid _____ grams 60
Water to make 1 liter.

The $\log I_0/I_R$ value was found to be 0.24.

In the following Table are given baths C to M of the invention, which had the same composition as bath (B) except that the acetic acid was replaced by the additives specified. The concentrations specified are those that gave the optimum results in another series of tests:

	Additive (g./liter)	$\log I_0/I_R$
C	Acrylic acid, 30	0.21
D	Lactic acid, 40	0.25
E	Cyanoacetic acid, 30	0.28
F	Succinic acid, 40	0.26
G	Tartaric acid, 20	0.23
H	Maleic acid, 20	0.25
I	Citric acid, 35	0.24
J	Citric acid, 35+surface-active agent 0.02	0.21
K	Citric acid, 35+surface-active agent 0.02	0.20
L	Citric acid, 35+surface-active agent 0.02	0.21
M	Acrylic acid, 125+surface-active agent 0.015	0.16

4
Example 2

A material having the arrangement of layers described in Example 1, was made in which the green-sensitized layer contained a dyestuff of the formula

15 Two areas were exposed to white light and two other areas to a combination of blue light and red light. Otherwise the procedure was the same as in Example 1. For treating one of the areas exposed to white light one of the areas exposed to colored light a rehalogenation 20 bath of the following composition was used:

Hydrochloric acid 37% strength _____ ml 130
Copper nitrate $3H_2O$ _____ grams 135
Acrylic acid _____ ml 125
25 Surface-active agent 0.1% _____ ml 15
Diphenyl-4:4'-dibiguanide hydrochloride _____ grams 3
Water to make 1 liter.

30 In the area exposed only to blue and red light the magenta dyestuff had retained its original color strength, while the color strength of the other area exposed to the same light, after treatment in a control bath of identical composition but not containing diphenyl dibiguanide, was considerably weakened. For the areas exposed to white 35 light, both after treatment with the bath containing dibiguanide and with the control bath, the value for $\log I_0/I_R$ was 0.16.

What is claimed is:

40 1. A bath suitable for rehalogenating metallic silver in a photographic material, which bath is substantially free from alkali metal ions and sulfate ions and which comprises a cupric salt, a hydrohalic acid and a water-soluble aliphatic carboxylic acid composed exclusively of carbon, hydrogen and oxygen.

45 2. A bath suitable for rehalogenating metallic silver in a photographic material, which bath is substantially free from alkali metal ions and sulfate ions which comprises a cupric salt, a hydrohalic acid, a surface-active agent and a water-soluble aliphatic carboxylic acid composed exclusively of carbon, hydrogen and oxygen.

50 3. A bath suitable for rehalogenating metallic silver in a photographic material, which bath is substantially free from alkali metal ions and sulfate ions and which comprises a cupric salt, a hydrohalic acid, a biguanide base and a water-soluble aliphatic carboxylic acid composed exclusively of carbon, hydrogen and oxygen.

55 4. A bath suitable for rehalogenating metallic silver in a photographic material, which bath is substantially free from alkali metal ions and sulfate ions and which comprises a cupric salt, a hydrohalic acid and acetic acid.

60 5. A bath suitable for rehalogenating metallic silver in a photographic material, which bath is substantially free from alkali metal ions and sulfate ions and which comprises a cupric salt, a hydrohalic acid and acrylic acid.

65 6. A bath suitable for rehalogenating metallic silver in a photographic material, which bath is substantially free from alkali metal ions and sulfate ions and which comprises a cupric salt, a hydrohalic acid and citric acid.

70 7. A bath suitable for rehalogenating metallic silver in a photographic material, which bath is substantially free from alkali metal ions and sulfate ions and which comprises a cupric salt, a hydrohalic acid, a surface-active agent and acrylic acid.

8. A bath suitable for rehalogenating metallic silver in a photographic material, which bath is substantially free from alkali metal ions and sulfate ions and which comprises a cupric salt, a hydrohalic acid, a surface-active agent and citric acid.

9. A bath suitable for rehalogenating metallic silver in a photographic material, which bath is substantially free from alkali metal ions and sulfate ions and which comprises a cupric salt, a hydrohalic acid, a surface-active agent, diphenyl-4:4'-dibiguanide hydrochloride and acrylic acid.

10. In a process for the production of a photographic image by the silver dye bleaching process, the step which comprises carrying out the silver bleaching after the dye bleaching in a bath which comprises a cupric salt, a hydrohalic acid and a water-soluble aliphatic carboxylic acid.
